UNITED STATES PATENT OFFICE

PHILIP J. HARRAH AND CHESTER P. HARRAH, OF BLOOMFIELD, INDIANA

CHECK CONSTRUCTION

Application filed June 28, 1929. Serial No. 374,461.

This invention relates to a door check construction.

The chief object of the invention is to provide a check construction which initially will permit the rapid closing of a door through approximately 75 to 85 degrees of closing and then permits closing at a decreased rate and without banging or slamming.

The chief feature of the invention consists in the construction of the hydraulic door check arranged such that the check is normally inoperative during the greater amount of door travel and becomes progressively operative as the door travel gradually decreases in the closing movement of the door.

The aforesaid progressive checking action is initially obtainable by the piston in the check encountering a liquid and moving through the same, the initial movement of the piston taking place through the air occupied portion of the cylinder. The subsequent travel of the piston is arranged to automatically restrict the by-passing of the liquid through the piston so that the rate of travel of the piston is decreased and the third and last stage of piston travel occurs under the aforesaid condition as well as in opposition to the compression of a bumper spring.

The full nature of the invention will be understood from the accompanying drawings and the following description and claims:

In the drawings Fig. 1 is a perspective view of the upper corner of a door and jamb with a spring and a check connecting the same, the check embodying the invention. Fig. 2 is a similar view showing three successive positions of the door in the closing movement. Fig. 3 is an enlarged central sectional view through the cylinder and piston construction embodying the invention.

In the drawings 10 indicates a jamb that pivotally supports a door 11, and a spring 12 is connected at opposite ends to each and normally tends to return the door toward the jamb and in closed relation when released from the open position. A bracket 13 herein shown mounted on the door pivotally supports an angle piece 15 as at 16. The angle piece in turn has a threaded engagement with a piston rod 17 and the ad-

justed position is maintained by means of a lock washer 18 and a nut 19.

A cylinder 20 has a closed end 21 with a tool engageable face, and co-axial therewith is an ear 22 apertured as at 23 to receive a pivot forming screw bolt 24 that pivotally supports an angle member 25 in turn pivotally supported as at 26 upon a bracket 27. The pivots 24 and 26 are at right angles to each other and a universal joint arrangement, therefore, is obtained in the aforesaid mounting. The piston rod extends through the cover cap 30, and the exterior thereof is formed as at 31 for tool engagement. The central opening 32 in the cover cap is threaded to receive a piston rod guide member 33 having a tool engageable extension 34 for mounting the same, and said guide member slidably supports the piston rod 17.

Positioned at the opposite end of the cylinder is an extended coil spring 35. In the last portion of the travel of the piston towards that end, said piston compresses the spring which thereupon serves as a bumper or cushion.

The end of the spring which terminates adjacent the piston herein is shown secured as at 36 to a disk 37 which cooperates with the piston. The piston construction includes a threaded end of the rod 38 that receives a plate 39 threadedly mounted thereon. A cup-shaped washer 40 of felt, leather, rubber, or the like, has its central portion retained by the washer 39 and another washer 41 against which bears a spring cup 42 locked by a nut 43.

In an air check construction the aforesaid parts are sufficient, but satisfactory operation does not obtain therefrom for some types of doors. The liquid but partially fills the cylinder as indicated at 45 for screen and light doors so that the piston in its initial travel passes through the air filled portion of the piston without any material resistance and then passes through the liquid containing portion of the cylinder. The liquid in that portion of the cylinder passes through a passage 46 which serves as a by-pass and the size of the by-pass determines the rate of travel of the piston through the liquid. This

by-pass controls the second stage of travel of the piston in the cylinder. An adjustment 70 for the by-pass may be provided. The liquid entirely fills the cylinder for very heavy doors.

The nut 43 projects beyond the end of the stem or rod 17 and forms a chamber 44 that communicates with passage 46 having the lateral outlet 47 above the piston, the chamber 44 constituting the outlet for the other end of the passage below the piston. The nut 43 is provided with one or more passages 49 that extends from chamber 44 to the exterior thereof, and the total cross sectional area of said passages is approximately half of the cross sectional area of the passage 46 or its lateral extension 47. When the disk 37 abuts the end of the nut 43 the liquid below the piston can only obtain access to the passage 46 for discharge above the piston and permit piston travel by said liquid passing through the passage or passages 49 in the nut. Since the cross sectional area of said passages is substantially half that of the passage 45 the rate of travel of the piston is substantially decreased over that previously obtained. The piston while moving under this relatively restricted flow of fluid has its third rate of travel.

As the aforesaid travel continues the spring 35 gradually compresses and offers increased opposition to the forward travel of the piston, and this occurs very near the end thereof so that a final cushioning is obtained as the last step of piston travel.

As shown clearly in Fig. 2 the initial closing movement of the door is from the position indicated at A to the position indicated at B, and during this amount of travel the piston moves through the air occupied portion of the cylinder. The piston moves through the liquid and before the nut chamber by-pass is sealed, the door travels from position B to position C. At the point C restricted fluid communication obtains by reason of the disk 37 and the final movement takes place under the aforesaid control and the last or immediate closing of the door from the position C to D occurs with the compression of and the cushioning by the spring 35.

The desirability of this progressively decreased rate of door closure is apparent when it is remembered that the rapid door movement takes place during the greater part of door movement so that for screen doors the doors are rapidly moved to substantially closed position and then are gradually eased into closed position without slamming or banging. When applied to storm doors the result is the same. The door opening is substantially closed with a rapid movement and then the final closing is but little in amount and relatively noiseless.

The quick closing of the door into substan-

tially closed position substantially prevents the admission of flies, etc., when the check is associated with the screen door and cold air when the check is associated with a storm door.

70

Since the springs only opposes door closing movement, in door opening movement it is not effective for any cushioning or opposition, also the liquid displaced by the piston in its return movement offers little or no resistance, consequently door opening is substantially instantaneous and effortless.

75

The invention claimed is:

1. The combination with two swingingly connected members, of a check construction connected at one end to one member and at its other end to the other member and including a liquid containing cylinder, a piston therein, a rod supporting the same and extending beyond the cylinder, a restricted communication through the piston and bumper spring interposed between the piston and the end of the cylinder opposite the rod supporting end and effective near the end of the piston travel for cushioning the same, said cylinder being but partially filled with liquid for relatively free movement of the piston through the air containing portion of the cylinder.

80

2. A check construction including a cylinder, a piston rod extending through one end thereof, a piston in the cylinder and on the free end of the rod, an adjustable by-pass permitting restricted communication between the chambers upon opposite sides of the piston, an auxiliary chamber at the piston end of the rod freely communicating with the by-pass and having an open end, passage means communicating with the auxiliary chamber and insuring communication to the auxiliary chamber at all times, a bumper spring in the cylinder operatively engageable by the piston, and means carried by said spring for sealing the open end of the chamber near the end of the piston travel for retarding the rate of piston travel.

85

In witness whereof, we have hereunto affixed our signatures.

PHILIP J. HARRAH.
CHESTER P. HARRAH.
